UNITED STATES PATENT OFFICE.

WILLIAM EVERETT VER PLANCK, OF ERIE, PENNSYLVANIA, ASSIGNOR TO GENERAL ELECTRIC COMPANY, A CORPORATION OF NEW YORK.

GOVERNING MECHANISM FOR INTERNAL-COMBUSTION ENGINES.

1,170,199.

Specification of Letters Patent.

Patented Feb. 1, 1916.

Application filed February 12, 1913. Serial No. 747,954.

To all whom it may concern:

Be it known that I, WILLIAM E. VER PLANCK, a citizen of the United States, residing at Erie, county of Erie, State of Pennsylvania, have invented certain new and useful Improvements in Governing Mechanism for Internal-Combustion Engines, of which the following is a specification.

- 10 The present invention relates to internal combustion engines of the so-called constant pressure type wherein the fuel is injected into highly compressed air in the cylinder or cylinders, the temperature of said air 15 being above the igniting temperature of the fuel and firing it. In such engines fuel is supplied under high pressure by one or more pumps to injectors or pulverizers located in the cylinders and from which it 20 is forced into the cylinders against the high pressure therein by what is commonly referred to as "blast air" received from a reciprocating compressor driven by the engine. The admission of blast air and fuel 25 to the cylinders is controlled by needle valves that are opened and closed at regular intervals by suitable mechanism driven by the engine. Owing to the high compression in the cylinders such engines have to be started 30 by some auxiliary source of power. The common arrangement is to provide blast bottles connected with the compressors for introducing fuel to the engine, and other bottles or receivers for supplying high pressure air for starting purposes. I propose to 35 do away with blast bottles and take air for injection purposes directly from the cooling coil of the compressor, which coil I purposely make large so that it has considerable 40 capacity. For starting I do away with the bottles or receivers and utilize an electric motor or the like for the purpose. This means then that until the engine and compressor have been given a number of strokes 45 there will be no blast air available. Since the fuel pumps are driven by the engine and since the fuel or needle valves are opened at predetermined intervals by the engine, it follows that unless means are provided to 50 prevent it, as the engine turns over, fuel will be forced by successive pump strokes into the injectors and either collect therein or work into the cylinders where it will cause dangerously high pressures on the first firing

stroke. To avoid this objection I provide a 55 governor for the fuel supply that is responsive to air pressure and by-passes fuel from each of the injectors or pulverizers until such time as the compressor has had an opportunity to build up an air pressure which is 60 superior to the compression pressure in the cylinder, after which the by-pass is closed and the engine operated in the normal manner. This pressure governor has no control over the fuel pump which may have any 65 suitable or usual form of governing mechanism to regulate its delivery. My improved arrangement also has the advantage that if one of the blast pipes is disrupted, as sometimes happens due to a structural weakness, the engine will be automatically shut down and this without the accumulation of 70 excess fuel in the injector or pulverizer to give trouble when the engine is re-started. I may also with material advantage utilize 75 this same governor to control the compressor by causing it to throttle its suction conduit when the pressure gets too high thereby insuring a constant pressure for the blast air.

In order to prevent the engine from racing, I provide an emergency speed governor which acts on the pressure governor in such manner as to relieve the air pressure therein and permit it to open the fuel by-pass valve or valves and thus shut down the engine by 85 cutting off its supply of fuel.

In the accompanying drawings which illustrate one of the embodiments of my invention, Figure 1 is a view in side elevation of an internal combustion engine arranged to drive an air compressor and electric generator; Fig. 2 is a detail sectional view of a governor controlled by-pass for the fuel; Fig. 3 is a longitudinal section of my improved pressure governor; Fig. 4 is a cross section of the same; Figs. 5 and 6 are respectively a side elevation and plan of the governor; Fig. 7 is a detailed view showing an emergency governor for relieving the pressure on the pressure governor 100 when the speed of the engine exceeds predetermined value; and Fig. 8 is a detailed view of a fuel injector or pulverizer.

10 indicates the base of the engine which is provided with as many cylinders 11 as 105 are necessary or desirable. Each cylinder may be provided with one or more pistons; I prefer to use two pistons in each cylinder,

the lower piston being connected to the crank shaft by a single rod and the upper piston by two side rods. Whether one piston or two is provided for each cylinder, it should, to attain the best results, compress the air therein to a temperature above the igniting temperature of the fuel. The fuel is introduced into each cylinder by an atomizer, or pulverizer 13 which may be of any suitable construction. This is shown in detail in Fig. 8 wherein 14 indicates a needle valve for controlling the admission of fuel to the engine, said valve being operated at regular intervals by means driven by the main shaft 12. Fuel is admitted to the pulverizer by the pipe 15 and blast air to the pulverizer by the pipe 16, which is connected to the distributing valve 17 of the air compressor 18. The compressor may be of any type capable of supplying fluid to the injector at a pressure above the compression pressure of the engine. Fuel is supplied to the pulverizer by the high pressure pump 19 of suitable construction, a separate pump being provided for each cylinder. The particular construction and arrangement of the pump is immaterial to the present invention. I prefer to drive the pumps from the main engine shaft. They may be governed in their normal action by any suitable means. Their effective action during the starting period of the engine and under emergency conditions is controlled by the air pressure governor and the emergency governor, to be described in detail hereinafter. The exhaust from the cylinders escapes by the exhaust pipe 21.

22 indicates a pipe for conveying cooling water to the engine cylinders.

40 23 indicates an electric generator whose rotor is directly mounted on the main shaft 12 of the engine. Current from this generator may be used for any suitable purpose. Mounted on the generator is an electric motor 24, used for starting purposes. The motor receives current from a storage battery or other source of electric energy. It is provided with the usual armature shaft and mounted thereon is a sprocket gear 26 which is connected by a chain or other means 27 with the main shaft of the engine.

Referring to Figs. 3 to 6, the construction of the pressure governor will be described. 30 indicates a base which supports the casing 31, the latter supporting a cylinder 32. Between the cylinder and the inner wall of the casing is a chamber 33 containing oil or other fluid, the object of which is to prevent air under high pressure from leaking between the inner wall of the cylinder and the plunger 34. The lower end of the cylinder is provided with a small opening 35 to establish communication between the cylinder and the chamber. It should be noted that 65 the cylinder 32 does not extend to the bot-

tom of the chamber. The object of this is to provide a recess or the like in which foreign particles can settle. The plunger is provided with a packing 36 at its upper end to prevent the escape of liquid and air or other fluids from the chamber. Air or other elastic fluid enters the chamber 33 from the air compressor 18, Fig. 1, by the nipple 37 and pipe 37a; the latter being connected to the distributing valve 17. As the pressure due to the compressor builds up the pressure in the chamber 33 increases which causes the plunger 34 to rise. The upward movement of the plunger is opposed by a lever 38 which has a fulcrum 39 carried by the link 40. The left-hand end of the lever is attached to a coiled extension spring 41, the latter being adjustable so that the pressure at which the governor will operate can be changed at will. 42 indicates a stop for limiting the downward movement of the lever under the action of the spring 41, and 43 indicates a stop for limiting the upward movement under the action of the plunger 34.

During the starting period of the engine it is necessary to prevent fuel from the pumps from entering the injectors or pulverizers and the cylinders. To this end a by-pass and valve are located in the pipe 15 leading from the fuel pump to the pulverizer. The construction of the by-pass is best shown in Fig. 2, wherein 45 indicates a fitting which is bolted or otherwise secured to the base of the pressure governor. It is provided with screw-threaded projections to receive the nipples 46 and 47, the former being arranged to receive fuel from the pump and the latter to deliver it to the pulverizer in the engine cylinder. Located inside of the fitting and extending in a horizontal plane is a check valve 48 that freely opens when fuel flows from the nipple 46 through nipple 47 and closes automatically to prevent fuel from flowing in the opposite direction. This is to prevent the air blast pressure from blowing fuel from the portion of the pipe 15 leading to the pulverizer through the by-pass when the controlling valve of the latter is open. To state the matter briefly 48 is a check valve opening toward the engine. 49 indicates a by-pass valve arranged in the by-pass 50, said valve being given a constant tendency to close by the coiled compressing spring 51. When the valve is in the position shown in Fig. 2 fuel can pass from the pump 19 through the nipple 46 past the valve 49 into the by-pass 50, from which it is returned to the overflow tank 52, Fig. 1, by the pipe 53. The by-pass valve is held shut during the normal operation of the engine by the spring 51, but during the starting period it must be held open until the air pressure due to the compressor reaches a predetermined value which is su- 130

pointed out, each pump is provided with a by-pass which is controlled by the pressure governor. It therefore follows that the simplest and easiest way to shut down the engine is to release the air pressure on the governor and cause it to open the by-pass valve. For this purpose the use of additional valves is obviated. It indicates the main shaft and particularly mounted upon one of the pump shafts is a lever 70 whose end 71 rests to move laterally against the action of the adjustable spring 72 when the speed of the engine reaches a predetermined value. This governor acts on the trigger 73 which normally occupies the position shown where one end of its arm 74 is in engagement with a shoulder on the lever 71. The trigger and lever are normally held in engagement by the spring 72. The lever 71 is provided with a catch 75 which is arranged to elevate the seat of the by-pass valve 77. This valve controls the passage of fluid through the pump. The valve is connected to the port 78 of Fig. 2, and the passage through the seat 75 and pipe connecting it with the valve 77 should be larger than that in the supply line which conveys air from the compressor to the oil containing chamber 33 of the governor so that the air can escape from the chamber faster than it can be admitted, thus permitting the plunger 34 to drop immediately to its lowest position and open the by-pass valve. Any liquid which may be contained in the chamber 33 above the valve 77 will be driven past the by-pass valve 77 into the cavity containing the parts of the emergency mechanism from which it escapes in a convergent way.

If it is sometimes necessary or desirable to stop the engine faster quickly by hand, to accomplish this the lever 71 is provided with a catch 75 which is projection 81, and located in the cavity 82 and arranged to engage it is such a way that is normally held in the position shown most securely when pushed inward by hand and engages the projection 81 and rocks the lever about its fulcrum, thereby disengaging the trigger and lever and causing the spring 72 to open the by-pass valve 77 and shut down the engine. Whether the trigger 73 is released by the speed governor or by hand the parts can be re-set by swinging the lower end of the lever 71 to the left until the projection on the trigger engages the shoulder on the lever.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure 130

by Letters Patent of the United States, is,—

1. The combination of an engine, a compressor, a fuel pump, an injector for the engine that receives fluid from the compressor and fuel from the pump, and a governor responsive to the pressure of the fluid delivered by the compressor for preventing fuel from entering the injector until said pressure exceeds a predetermined value.
2. The combination of an engine, a compressor driven thereby, a fuel pump, an injector for the engine that receives fluid from the compressor and fuel from the pump, a by-pass for the fuel supply located between the pump and injector, and a governor sensitive to a condition of the fluid passing through the compressor which holds the by-pass open until the pressure of the fluid delivered by the compressor exceeds a predetermined value.
3. The combination of an engine, an elastic fluid compressor, a fuel pump, an injector for the engine that receives fluid from the compressor and fuel from the pump, and a governor for controlling the admission of fuel to the injector which comprises a member sensitive to the pressure of said fluid, a means acting in opposition to the member, and a valve controlling the passage of fuel through the injector.
4. The combination of an engine, an elastic fluid compressor, a fuel pump, an injector for the engine that receives fluid from the compressor and fuel from the pump, a main governor responsive to the pressure of the fluid delivered by the compressor for preventing fuel from entering the injector until the fluid pressure exceeds a predetermined value, and an emergency speed governor driven by the engine for by-passing fuel from the injector.
5. The combination of an engine, an elastic fluid compressor, a fuel pump, an injector for the engine that receives fluid from the compressor and fuel from the pump, a main governor responsive to the pressure of the fluid delivered by the compressor for preventing fuel from entering the injector until the fluid pressure exceeds a predetermined value, an emergency governor responsive to an operating condition of the engine, and a valve controlled thereby which relieves the fluid pressure on the governor and prevents fuel from entering the injector.
6. The combination of an engine, an elastic fluid compressor, a fuel pump, an injector for the engine that receives fluid from the compressor and fuel from the pump, a by-pass for the fuel which is open when the engine is idle, a governor responsive to the pressure of the fluid delivered by the compressor which closes the by-pass when said pressure exceeds a predetermined value, and an emergency governor driven by the engine

which when its speed exceeds a predetermined value assumes control of the fuel supply to the exclusion of the pressure governor.

7. The combination of an engine, an elastic fluid compressor, a fuel pump, an injector for the engine that receives fluid from the compressor and fuel from the pump, a by-pass and valve for the fuel supply located between the pump and injector, a governor having a member movable in response to the pressure of the fluid delivered by the compressor for closing the by-pass valve when said pressure reaches a predetermined value, a second by-pass and valve, and an emergency speed governor driven by the engine which when it acts relieves the fluid pressure on said member and permits its governor to open the first mentioned by-pass.

8. The combination of an engine, an elastic fluid compressor driven thereby, a fuel pump, an injector for the engine that receives fluid from the compressor and fuel from the pump, a governor responsive to the pressure of the fluid delivered by the compressor which determines when fuel shall be delivered to the injector, and means also actuated by the governor for regulating the pressure of the fluid delivered by the compressor.

9. The combination of an engine, an elastic fluid compressor driven thereby, a fuel pump, an injector for the engine that receives fluid from the compressor and fuel from the pump, a governor comprising a member movable in response to changes in pressure of the fluid delivered by the compressor and a means acting in opposition thereto, and a throttle valve for the intake of the compressor which is moved by said member.

10. The combination of a multi-cylinder engine, an elastic fluid compressor, a fuel pump for each cylinder, a fuel injector for each cylinder, a governor responsive to changes in pressure of the fluid delivered by the compressor which determines when fuel shall be delivered by the pumps to their respective injectors, and means responsive to an operative condition of the engine for rendering the governor inactive.

11. The combination of a multi-cylinder engine, an elastic fluid compressor, a fuel pump for each cylinder, a fuel injector for each cylinder, a governor responsive to changes in pressure of the fluid delivered by the compressor, a by-pass valve between each pump and its fuel injector that normally tends to close and is held open by the governor until the compressor pressure exceeds the compression pressure within the engine cylinders, and means acting in response to an emergency condition for relieving the fluid pressure within the governor and permitting it to open said by-pass valves.

12. In the combination of an engine, a compressor, a fuel pump, an injector, and a governor responsive to the pressure of the fluid delivered by the compressor which comprises a plunger and cylinder to which fluid from the compressor is admitted, a lever acted upon by the plunger, a spring for loading the lever, a by-pass valve in the pump circuit between it and the injector, and a means moved by the lever for holding the valve open until the plunger has moved the lever a predetermined distance. 5
13. In the combination, a multi-cylinder engine, a compressor, a fuel injector for each cylinder, a fuel pump for each cylinder, a by-pass in each pump circuit between said pump and its injector, and a governor comprising a plunger and cylinder to which fluid from the compressor is admitted, a lever moved by the plunger, a means acting on the lever in opposition to the plunger, and a bridge piece movable with the lever for simultaneously controlling the by-pass valves. 10
14. In the combination, a multi-cylinder engine, a compressor, a fuel injector for each cylinder, a by-pass in each pump circuit between said pump and its injector, and a governor comprising a plunger and cylinder to which fluid from the compressor is admitted, a lever moved by the plunger, a means acting on the lever in opposition to the plunger, a bridge piece movable with the lever for simultaneously releasing the by-pass valves, and a valve which controls the admission of fluid to the compressor and is actuated by said lever. 15
15. The combination of an engine, a fluid compressor driven thereby, a fuel pump, an injector for the engine that receives fluid from the compressor and fuel from the pump, and a means responsive to the pressure of the fluid delivered by the compressor for preventing fuel from entering the injector when said pressure falls below a predetermined value. 20
16. In an apparatus of the character described, the combination with an engine having a fuel injector and a compressor driven thereby for supplying air to the injector, of a governor comprising a base having a liquid containing chamber, a cylinder that extends into said chamber and is provided with an opening communicating therewith, a plunger in the cylinder, a lever that is moved by the plunger, a spring acting on the lever in opposition to the plunger, a conduit admitting fluid under pressure from the compressor to the chamber, a valve which throttles the intake of the compressor, and means connecting said valve to the lever. 25
17. In an apparatus of the character described, the combination with an engine having a fuel injector, a compressor driven thereby for supplying air to the injector, and a pump for supplying fuel to it, of a governor comprising a base having a liquid containing chamber, a cylinder that extends into said chamber and is provided with an opening communicating therewith, a plunger in the cylinder, a lever that is moved by the plunger, a spring acting on the lever in opposition to the plunger, a conduit admitting fluid under pressure from the compressor to the chamber, a valve that has a tendency to close and controls the delivery of fuel from the pump to the injector, and means actuated by the lever for opening said valve when the pressure in the chamber is below a predetermined value. 30
18. In an apparatus of the character described, the combination with an engine having a fuel injector, a compressor driven thereby for supplying air to the injector, and a pump for supplying fuel to it, of a governor comprising a base having a liquid containing chamber, a cylinder that extends into said chamber and is provided with an opening communicating therewith, a plunger in the cylinder, a lever that is moved by the plunger, a spring acting on the lever in opposition to the plunger, a conduit admitting fluid under pressure from the compressor to the chamber, a valve that has a tendency to close and is actuated by the lever through lost motion, said valve controlling the delivery of fuel from the pump to the injector, and a second valve that is connected to and moves with the lever under all conditions for throttling the intake of the compressor. 35

In witness whereof, I have hereunto set my hand this 7th day of Feby., 1913.

WM. EVERETT VER PLANCK.
